UNITED STATES PATENT OFFICE.

EMIL STROM, OF CHICAGO, ILLINOIS.

DESIGN FOR A SMOKING-PIPE.

55,443.

Specification for Design.

Patented June 8, 1920.

Application filed November 10, 1919. Serial No. 337,032. Term of patent 3½ years.

To all whom it may concern:

Be it known that I, EMIL STROM, a citizen of Finland, residing at Chicago, in the county of Cook and State of Illinois, have invented a new, original, and ornamental Design for Smoking-Pipes, of which the following is a specification, reference being had to the accompanying drawing, forming part thereof.

The figure is a view in side elevation of a smoking pipe, showing my new design.

I claim:

The ornamental design for a smoking pipe, as shown.

EMIL STROM.
